Caleb K. Colby,

By his Attorneys,

Burke, Fraser & Connell,

UNITED STATES PATENT OFFICE.

CALEB K. COLBY, OF BROOKLYN, NEW YORK.

ATTACHMENT OF WATCH-PENDANTS.

SPECIFICATION forming part of Letters Patent No. 239,732, dated April 5, 1881.

Application filed December 6, 1880. (Model.)

To all whom it may concern:

Be it known that I, CALEB K. COLBY, a citizen of the United States, residing in Brooklyn, Kings county, New York, have invented 5 certain Improvements in Watches, of which the following is a specification.

This invention relates to improvements in what are known as "stem-winding" as distinguished from "key-winding" watches, the object 10 being to cheapen the construction without detracting from the convenience or the dust-proof character of the watch, and to provide a stem, with the necessary winding appliances, that is entirely independent of both the case and the 15 movement—that is to say, the stem is not directly connected with either the case or the movement, and may be applied to another case and another movement in a few moments, or as readily as the movement can be taken out of 20 an ordinary case.

In the drawings, which serve to illustrate my invention, Figure 1 is a transverse mid-section taken through the case of a watch embodying my improvements, the view being on a larger 25 scale. Fig. 2 is a plan or face view of the movement resting in the ring to which the stem is attached. Fig. 3 is a side or edge view of Fig. 2. Fig. 4 is a plan of the case detached, the bezel bearing the crystal shown 30 as overlapping the case proper. Fig. 5 is a transverse mid-section of the case detached, showing the parts separated.

A represents a watch-movement which consists of the two movement-plates bearing the 35 works or gearing, the dials, and the hands.

B is the case which incloses the movement. This case may be made of any form or material, and consists of the main portion, lettered b, which is in the form of a cup with an 40 open top, its sides and back being in one piece, and the bezel c, which holds the crystal. The bezel is sprung upon the body in a well-known way. The main part or body of the case has a notch or recess, d, formed in one side to receive the stem or pendant when the parts are 45 put together, as in Fig. 1. My case is adapted to be made wholly of celluloid or other similar non-metallic material, as the pendant, which is always of metal, is not attached to the case.

50 C is the stem or pendant, which is attached rigidly to an open band or ring, a, adapted to fit and receive the movement. The stem

contains the ordinary spindle or mechanism for winding, the same being operated by means of the usual knob or ball, g. This mechanism 55 being well known, and forming no part of my present invention; I have not thought it necessary to illustrate it more fully.

To prevent the dust from entering the case around the stem, I employ a self-adjusting 60 rose or flange, e, forming part of a sleeve, f, which surrounds the neck of the stem. The flange is kept pressed up to the case by means of a spring arranged inside the sleeve f, which spring abuts against a shoulder on the stem. 65

It will be observed that my watch comprises three principal parts, wholly detached or detachable from each other, and adapted to be manufactured and sold separately. These are the case, the movement, and the stem with its 70 attached band or ring a. Movements adapted for stem-winding are manufactured by the various watch companies to standard sizes; and the rings a may be manufactured to fit the different sizes of movements, and the stems 75 be attached thereto. It will then only be necessary to set the movement in the ring, secure it by a screw in the way usually employed in fixing the movement, and the watch is ready 80 to case.

The ring a having a bearing all around the movement-plates, it will be obvious that it may be handled by the pendant without danger of springing the plates or putting the delicate machinery of the movement out of adjustment; and it is a simple and cheap way of attaching the stem to the movement as well as the safest. The two parts of the case being sprung together instead of onto the movement or the ring a, the strain and jar produced in 90 applying and removing the case can have no injurious effect on mechanism of the watch.

I am aware that cases provided with a winding stem or pendant have had a ring to receive the movement hinged thereto; and I am also 95 aware that movements have had winding-pendants secured to the movement-plates by screws and inclosing-cases sprung onto said movements. These, however, differ essentially from my invention in both construction and 100 purpose.

I claim—

1. An open band, a, constructed to embrace and hold a watch-movement and to fit into an

inclosing-case, and provided with a winding-stem, C, rigidly secured thereto, substantially as and for the purposes set forth.

2. The combination of a watch-case composed of two parts, one arranged to be sprung onto the other, the major part *b* having a recess, *d*, for the stem, and an open band or ring, *a*, to receive the movement and to fit into the case, said band having a winding stem or pendant fixed thereto, substantially as and for the purposes set forth.

3. The combination, to form a watch, of a case composed of two parts, one arranged to be sprung onto the other, the major part *b* hav-

ing a recess, *d*, for the stem, an open band or ring, *a*, to receive the movement and to fit into the case, a winding stem or pendant, C, secured rigidly to the ring *a*, and a movement, A, adapted to fit into the ring or band *a*, all constructed and arranged substantially as set forth.

In witness whereof I have hereunto signed my name in the presence of two subscribing witnesses.

CALEB K. COLBY.

Witnesses:

ARTHUR C. FRASER,
HENRY CONNETT.
